UNITED STATES PATENT OFFICE

EDOR DAHL, OF MINNEAPOLIS, MINNESOTA, ASSIGNOR TO GROFF PAPER COMPANY, OF ST. PAUL, MINNESOTA

DESIGN FOR AN EMBOSSED PAPER NAPKIN

Application filed December 4, 1930. Serial No. 37,886. Term of patent 14 years.

To all whom it may concern:

Be it known that I, EDOR DAHL, a citizen of the United States, residing at Minneapolis, in the county of Hennepin and State of Minnesota, have invented a new, original, and ornamental Design for Embossed Paper Napkins, of which the following is a specification, reference being had to the accompanying drawing, forming part thereof.

Fig. 1 is a plan view of an embossed paper napkin showing my new design.

Fig. 2 is a view of one corner of the napkin on an enlarged scale.

I claim:

The ornamental design for an embossed paper napkin, as shown.

In testimony whereof I hereunto affix my signature.

EDOR DAHL.
